BALL CASTING MACHINE

Willard C. Brinton, New York, N. Y.

Application September 23, 1944, Serial No. 555,442

7 Claims. (Cl. 22—75)

1

This invention relates to improvements in automatic machines for casting grinding balls and similar articles.

Wherever rocks and ores are to be reduced to a powder for any reason, or purpose, as for preparing metaliferous ores for treatment for flotation, they are, as a rule, crushed and then ground in a ball or rod mill. In the grinding operation the balls employed are subject to the abrasive action of the materials ground which soon reduces the size of the balls to such an extent that they must be replaced. Balls for grinding mills are either forged from steel or cast from iron, and must have the required grain structure and hardness for long life.

Balls from cast iron are usually cast in water cooled molds and thus acquire a "chilled" outer surface that is hard and a grain structure which is tough, which characteristics make them last a long time compared with balls cast in sand molds.

Various kinds of machines have been invented and used for casting grinding balls, some of which are to a certain degree, automatic.

It is the object of this invention to produce a grinding ball casting machine which shall be of a simple and substantial construction and which can be manufactured and sold for less than similar machines of different construction.

Another object is to produce a machine of the type specified which can be made almost entirely from commercial forms of structural steel thereby eliminating to a great extent the cost incident to the preparation of expensive patterns and special tools.

A further object of this invention is to produce a ball casting machine having two spaced and inclined channels for the reception of substantially cubical mold blocks and to provide the same with means for moving the blocks upwardly in one channel and downwardly in the other channel and to provide means for shifting the blocks from one channel to the other.

Another object is to produce a machine of the type specified in which the mold blocks move upwardly in straight rows during the casting operation in response to a force applied to the lowest block, as distinguished from circular paths, whereby the blocks may be readily cooled.

Another object is to produce a casting machine in which the mold blocks may be rocked relative to each other while the metal is still molten and while it is setting so as to facilitate the removal of the balls.

A further object is to produce a machine in which the mold blocks are caused to move over

10 a convex supporting surface to break the groove metal or sprue.

Another object is to produce a ball casting machine in which the mold blocks are arranged in substantially straight and horizontally inclined rows and the metal allowed to flow downwardly through surface grooves that are in communication with the mold gate and in which means is provided for partially cutting and for chilling the metal in the block grooves to facilitate breakage.

15 A further object is to produce a machine in which the expansion of the mold blocks is utilized for breaking the groove metal that joins the sprues.

20 Another object is to produce a machine having separate mold blocks in which the force exerted on them during the shifting of the blocks tends to urge their contacting surfaces into engagement with each other and in which the expansion, due to the heat, also serves to urge the adjacent block surfaces into closer contact.

25 A further object is to produce a machine in which the degree of cooling can be regulated by changing the position of the pouring means.

20 The above and any other objects that may become apparent as the description proceeds are attained by means of a construction and an arrangement of parts that will now be described in detail and for this purpose reference will be had to the accompanying drawings in which the invention has been illustrated, and in which:

35 Figure 1 is a top plan view of the casting machine, shown in a more or less diagrammatic manner, with portions thereof omitted and other portions broken away;

Figure 2 is a side elevation of the machine shown in Figure 1;

Figure 3 is a transverse section taken on lines 3—3, Figures 1 and 2;

40 Figure 4 is a top plan view of a mold block;

Figure 5 is an end elevation of the block shown in Figure 4;

Figure 6 is a side elevation of the block shown in Figure 4;

45 Figure 7 is a transverse section taken on line 7—7, Figure 4;

Figure 8 is a transverse section similar to that shown in Figure 7, but showing a modified construction in which the center part of the block is made from highly heat conductive material, such as copper;

50 Figure 9 is a top plan view of a mold block whose outer surface is provided with a replaceable layer of poor heat conducting material;

Figure 10 is an end view of the block shown in Figure 9;

Figure 11 is a fragmentary top plan view showing the relationship of the several parts and the position of the groove metal notching wheel;

Figure 12 is a side elevation of the part shown in Figure 11;

Figure 13 is a section through a sprue showing the hollow material, the same as it appears immediately before the opening is closed by the flowing metal;

Figure 14 is a transverse section taken on line 14—14, Figure 13;

Figure 15 is a fragmentary top view showing means for rocking the blocks as they are moved upwardly in one of the channels;

Figure 16 is a side elevation of the rocking means shown in Figure 15;

Figure 17 is a top plan view of a mold block showing each side provided with short transverse ribs for cooperation with the rocking means;

Figure 18 is an end elevation of the block shown in Figure 17;

Figure 19 is a side elevation of the block shown in Figure 18;

Figure 20 is a section taken on line 22—22. Figure 1 and shows a means for bending the row of blocks so as to effect a breaking of the groove metal;

Figure 21 shows the mold blocks arranged in one position with the groove on the lower side of the center line;

Figure 22 is a view similar to that shown in Figure 23, but shows the groove on the upper side of the center line;

Figure 23 is a diagram showing the relative positions and the relation of the several elements of the machine.

Referring now to the drawings and more particularly to Figures 1 and 2, reference numeral 5 designates the floor or some other supporting surface on which the machine rests. One end of the machine is supported between a pair of vertical pipes 6, whose enlarged bases 7 rest on the floor. Sleeves 8 are slidably connected with pipes 6 and are held in vertical position by means of pins passing through the openings 9. A pipe 10, which has been indicated by dotted lines in Figure 2, connects the sleeves 8. The upper end of the frame, which will now be described, rests on this transverse supporting member.

The casting machine comprises a frame having three parallel guide members which have been designated by reference numerals 11, 12 and 13. These members are constructed so as to be of rectangular cross section and hollow, as shown in Figure 3. In the actual construction they are each formed from two six-inch channels having two-inch flanges, the flanges being welded so as to form a watertight joint, the ends of these guide members are also closed with a watertight closure which does not show in the drawings. The several guides are spaced as shown in Figure 3 so as to form channels A and B. The bottoms of the channels are formed by hollow members 14 and 15, which are of the same size and constructed in the same manner as guides 11, 12 and 13. The bottom members 14 and 15 are electrowelded to transversely extending pipes 16, which hold them in spaced position. It will be seen from Figure 3, that bottom members 14 and 15 are spaced apart at the center so as to form a channel C in which is located a pipe 17, to which reference will hereinafter be made in greater particularity. Secured to the sides of the hollow bottom members 14 and

15, are outwardly extending brackets 18, which may be electrowelded thereto. These brackets have elongated openings 19. Brackets 20 are electrowelded to the bottoms of the guides 12 and 13 and bolts 21 extend through the brackets 18 and 20 and secure the guide members to the hollow bottom members in a predetermined relation. The parts are adjusted in such a way that channels A, B and C are of uniform width throughout their length. Electrowelded or otherwise secured to the frame near the lower end thereof, as viewed in Figure 11, is a large transversely extending pipe 22, or other equivalent member, that supports the lower end of the frame from the surface of the floor and permits a rocking movement thereof so as to allow the inclination to be adjusted by means of the support shown at the lefthand end of Figure 2. Pipe 17 is continuous, as shown in Figures 1 and 2, and at its lower end it is provided with a cross head 23. Secured to the upper end of pipe 17 is a cross head 25 which has an upwardly extending portion 26 from which a pusher bar 27 extends rearwardly. A pusher bar 28, similar to that designated by reference numeral 27, is secured to one end of cross head 23. It will now be evident that whenever the pipe is reciprocated, the two pusher bars 27 and 28 will move in the same direction and to the same extent.

It will be observed that the guide 13 extends downwardly to a greater distance than guides 11 and 12 and that guide 12 extends upwardly beyond guides 11 and 13, all for a purpose which will hereinafter appear.

Reference will now be had to Figure 22 from which it will be seen that the cross head 23 is secured to the end of a piston rod 30 that extends into a cylinder 31. A piston 32 is secured to the inner end of the piston rod and is urged against the end 33 of the cylinder by means of a powerful spring 34. A three-way valve 35 is connected with the cylinder and is in communication with the inner end thereof through a passage 36. The outlet port of this valve has been designated by reference numeral 37 and the inlet port, which is connected with a source of air under pressure (not shown) has been designated by reference numeral 38. The rotatable valve plug 39 has a handle 40 provided at its upper end with a heavy weight 41. When the handle 40 is rocked from the full, to the dotted line position shown in Figure 23, it closes the inlet port 38 and opens communication between the passage 36 and the outlet port 37, whereby the spring 34 will function to return the parts to the full line position shown in Figure 23. A valve control bar 42 has one end secured to the cross head 23 and extends across the valve handle 40. This bar has an elongated notch 43 in which pin 44, which is connected with the handle 40, moves. In the position shown in Figure 23, the valve has just been moved to such a position that the interior is connected with the compressed air and the piston will therefore begin to move towards the left and when the pin 44 contacts the wall at the righthand end of notch 43, it will move the valve handle over dead center so as to permit the weight to throw it into the dotted line position whereupon the valve will be in a position to communicate the interior of the cylinder with the outlet port.

It will be observed that this mechanism is in effect a motor in which movement is effected in one direction by means of air pressure and the other by means of spring 34 and that it will con-

tinue to operate in this manner as long as it is supplied with compressed air.

Although it has not been shown in the drawing, the air is admitted to the valve through a very small opening so as to limit the rate at which the cylinder moves.

Attention is called at this point to the fact that the guides 11, 12 and 13, as well as the hollow bottom members 14 and 15 are water cooled, the water entering through the pipes designated by reference numerals 45 and leaves through the pipes designated by reference numeral 46. The circulation of water is effected by any suitable means, which has not been shown.

Positioned in the channels A and B and resting on the bottom members 14 and 15 are mold blocks 47 of a construction which will now be described.

Referring now more particularly to Figures 4 to 10, it will be seen that the blocks 47 are of almost cubical shape, the top view as shown in Figure 4 being a square and in actual construction for use in molding a three-inch ball, the blocks are five inches square and six inches deep and are formed from cast iron, except as will hereinafter be explained. The upper surface of each block has a groove 48 whose bottom is inclined slightly towards the center in the manner shown in Figure 5. The opposite ends are provided with semispherical depressions 49 and with gate openings 50 that extend to the top of the block and intersect the groove 48. When the blocks are placed in end to end relation as shown in Figures 1, 2, 21 and 22, the semispherical depressions supplement each other to form spherical molds for the reception of the molten metal. It is sometimes desirable to effect a more rapid dissipation of the heat from the molten metal, than would be effected in a solid cast iron mold block and when this is the case, the blocks are molded with a cavity 51 that extends upwardly from the bottom in the manner shown in Figure 8 and this cavity is filled with copper or any other suitable metal 52 of high heat conductivity that has a sufficiently high melting point to make it suitable for this purpose. It will be seen that when the blocks are in position as shown in Figures 1 and 2, their lower surfaces rest on members 14 and 15 and their sides are adjacent the guides 11, 12 and 13 and since all of these supporting and guide members are water cooled, the heat from the molten metal is rapidly dissipated.

In Figures 9 and 10, a slightly modified form of block has been shown. In this modification the upper surface has a depressed area whose bottom has been designated by reference numeral 53. Positioned in this depressed area is a block 54 of refractory poor heat conducting material, such as fireclay. This block has a groove 48a that communicates with the gate 50a. The poor heat insulating material 54 retards the cooling of the molten metal. In order to position the block 54 the side walls of the depressed area are provided with inwardly extending projections 55 that fit into suitable depressions in the sides of the block. Any other suitable means for positioning these blocks may be substituted.

With the insert 54 of poor heat conducting material, the metal will not as readily solidify in the grooves as when it is poured directly onto a cast iron surface. Instead of a thick block like shown, the grooves 48 in the cast iron blocks may be painted or otherwise covered with a thin layer of fireclay, or other suitable material so as to form a heat insulating layer.

The blocks 47 are positioned in channels A and B in sufficient number to completely fill the same from end to end as indicated in Figures 1 and 2 and are moved longitudinally in the channels by the reciprocation of the pusher bars 27 and 28 and transferred from one channel to the other by transferring means which will now be described.

The distance that the pipe 17 and the cross heads which are attached thereto reciprocate at each cycle of rotation is equal to twice the length of the blocks, for a reason which will hereinafter be pointed out. When the channels A and B are full of blocks, the blocks will be moved only the length of one block during each cycle of rotation for the reason that there is a lost motion at the point D Figure 23 equal to the length of a block. At the end of each cycle of rotation, the blocks are in the positions shown by full lines in Figure 1 and it is now necessary to move the lowermost block in channel B to the dotted line position at the lower end of channel A and to move the block designated by 47X at the upper end of channel A to the dotted line position in front of the pusher bar 27. To effect this transfer of blocks from one channel to the other, certain mechanisms have been provided which have been shown in a more or less diagrammatic manner in Figure 23 to which reference will now be made. At the lower ends of the guide members and channels A and B there is a slide designated by reference numeral 56, which has a finger 57 pointing towards the blocks. This slide moves in a guide which has not been shown. A cable 58 is attached to one end of the slide and after passing over one or more pulleys 59, terminates in a weight 60. This weight tends to move the slide to the full line position. Extending from the slide is another cable 61 that passes around the pulley 62 and is anchored to a stationary member at point 63. An arm 64 is connected with the cross head 29 and carries a pulley 65 which contacts the bight of the cable, all as shown in full lines in Figure 23. When the cross head moves towards the left into the broken line position, the bight of the cable is increased and the slide 56 is moved into the broken line position. It will be seen that the slide 56 has a projection 66 and that there is a pawl 67 pivoted to a stationary part of the machine at 68. A spring 69 tends to rotate the pawl in a clockwise direction. When the slide reaches the broken line, the projection 66 will pass by and engage the hook at the end of pawl 67 and the slide will therefore remain latched in this position until released. The release of the slide is effected by means of a pin 70 that is carried by arm 64 and which engages the pawl and moves it to releasing position just before the cross arm reaches the return end of its stroke. When the pawl releases the slide 56, it will move in response to the tension produced by weight 60, thereby engaging the lowermost block in channel B (Figure 1) and move this block to the full line position in channel A.

At the upper end of the machine the block 47X must be moved to the dotted line position in channel B and this is effected by means of a transfer mechanism comprising a slide 71 that moves in a suitable guide, not shown, and to which finger 72 is pivotally connected at 73. A spring 74 tends to hold this finger against the stop 75. A cable 76 is attached to the slide 71 and after passing over one or more pulleys 77, is attached to a weight 78. In the full line position shown in Figure 26, the weight is at its uppermost position. It will be observed that the cross head 75 has an arm 79 to the end of which a pulley 80

is attached. A cable 81 is attached to the slide 71 and after passing around the pulley 82, is anchored to a stationary part of the machine at 83. A bight of the cable passes around the pulley 80. When the arm 79 moves from full line to dotted line position, it permits the weight 78 to move the slide 71 towards the broken line position and in this movement the finger 72 engages the side of the block 47 shown in broken lines and transfers it to the broken line position in channel B. When the slide reaches this position, the cross head and the attached parts are in the broken line position. An arm 84 is attached to the cross head and carries a downwardly extending plate 85 on one side. A lever 86 is pivoted to arm 84 at points 87 and is acted on by a spring 88 which tends to move it in a counter-clockwise direction about the pivot 87. The free end of the lever has a downwardly projecting curved plate 89 that overlaps the corresponding side of a block as shown in Figure 23. With the parts in the position shown in Figure 23, it is apparent that if the arm 84 begins to move towards the left, it will carry with it the block 47 that is positioned between plates 85 and 89. When the parts move towards the left, the end block in channel A will be separated from the next block and will be carried a distance of its own length before the pusher bar 28 will engage the lowermost block in channel A. After this, the whole row of blocks in channel A will move the length of one block. Due to the lost motion above referred to, the upper block in channel A will move twice its own length, while the other blocks in this channel will move only their own length and as a result of this there will be a space indicated by Y in Figure 23 that is equal to the length of a block. There is a solid plate 90 that extends beyond the upper ends of guides 11 and 13 for the support of the blocks and this is provided with an opening 91 through which the balls drop after they are removed from the molds.

It is apparent that the separating device comprising the lever 86 and associated parts must be released as the parts approach the end of their stroke and to effect this a stop 92 is positioned in the path of the upper end of lever 86. The action of this stop is to move this lever to the position shown in broken lines. It is further apparent that some means must be provided for holding this lever in inoperative position until the parts return to a position in which another block is to be grasped and this is effected by means of a friction brake mechanism comprising a lever 93, which is pivoted at 94 and has an end 95 bent so as to engage the lever 86 and hold it against movement due to the action of spring 88. The pivotal connection at 94 is such that it offers a considerable frictional resistance against movement and this is effected by any one of the many well known means employed for this purpose in different types of machines. A stop 96 is so positioned that when the parts approach their lowermost limit of travel, the two levers 86 and 93 will engage this stop and this will remove the end 95 from lever 86 and permit the spring to function so as to bring the part 89 into block engaging position. The parts are now in such a position that at the beginning of the next cycle of rotation, another block will be separated from the line of blocks in channel A and moved to a point on the upper side of opening 91, whereupon the ball casting in the mold can be separated and allowed to drop through the opening 91 from whence it passes through a tubular conduit 97

to a tumbling barrel 98 which is rotated by suitable means.

From the above description it will be apparent that with the mechanism illustrated, an intermittent shifting of the mold blocks can be effected, the blocks being periodically moved in their channels the length of one block and the upper block of channel A being moved the length of two blocks so as to effect a separation for the purpose of 10 removing the castings. So long as air is supplied to the cylinder 31, this movement will continue. The pipe supplying air from the storage tank to the three-way valve has not been shown, but it is provided with one or more valves positioned at strategic places around the machine so that the operator can stop the machine whenever he wants to by closing any one of these valves.

The pressure exerted by the pusher bars in 20 moving the blocks upwardly in channel A serves to force the contacting surface of adjacent blocks 25 towards each other to close the mold. The adjacent block surfaces do not necessarily have to be finished, but can be in the condition in which they arrive from the mold, because any molten metal that penetrates the thin space between these blocks will immediately become chilled and seal the mold.

Since it is the purpose of this machine to make 30 balls or other similar articles, it is necessary to provide molten metal and to deposit this in the 35 grooves 48 where it may run downwardly and enter the gates and fill the molds. In Figure 2, a ladle 99 has been shown. This is supported 40 on trunnions 100. The carriage for the ladle 45 has not been illustrated as any of the ordinary 50 and well known ladle supports can be used. The pouring lip of the ladle has been designated by 55 reference numeral 101. Molten metal is poured from the ladle into the groove 48 and runs downwardly from one block to the other and since the gates 50 intersect the grooves 48, molten metal will flow through the gates and into the mold depressions, filling the same. Due to the fact that the gates are positioned to one side of the groove, the metal will be given a rotary motion as it 60 enters the gate opening. This rotary motion provides the metal sprue, with a center opening like that indicated by reference numeral 102 in Figure 3 where the sprue has been designated by 65 reference numeral 103. The opening in the sprue permits any air or gas to escape and after the mold has been completely filled, opening 102 will also close. The rotary motion of the molten metal has been designated by arrow 104 in Figure 14. The different sprues are connected from one 70 block to the other by means of the strips of groove metal 105.

Since the groove metal must be separated or 75 broken before the blocks can be separated, means 80 has been provided to notch the metal and to subject it to a chilling action to make it brittle. For the purpose of notching and chilling the groove metal, a wheel 106 has been mounted for rotation about a bearing 107 that is carried by the front end of an arm 108 which in turn is pivotally connected at 109 to the vertical flange 110 of an angle bracket whose horizontal flange 111 is secured to the guide 13 by means of bolts 112. The wheel 106 is provided with sharp steel teeth or projections 113 that are adjusted to travel in the 85 grooves 48. This wheel is positioned directly 90 above the point where the metal is poured and therefore engages the groove metal before it hardens. The teeth cut depressions 114 in the groove metal in the manner shown in Figure 11. 95 By the time the molds reach the upper end of

channel A, the groove metal will have cooled to such an extent that it will be very brittle and can be readily broken at points 114. In order to expedite the cooling of the groove metal a massive metal wheel 115 is mounted on a support like that employed in connection with wheel 106 and positioned so as to engage the upper surface of the groove metal for the purpose of abstracting heat therefrom. Due to the heat absorptive action of the mold blocks and to the further heat absorptive action of wheels 106 and 115, the groove metal will cool very rapidly so as to be entirely solidified at the upper end of channel A.

A short distance below the point of pouring and at a point where the metal is still soft, a means has been provided for rocking the blocks. This means comprises two springs 116 that are secured to and extended downwardly from a cross member 117. These springs engage the blocks on opposite sides of their center lines. For the purpose of making these springs effective to rock the blocks, the latter has been constructed with their bases in a broadly convex shape. The convex curvature is effected by three straight surfaces comprising a center straight surface F and two upwardly inclined straight surfaces G, as shown in Figure 18. The center surface F rests on the upper surface of the bottom members 14 and 15 so as to be in good heat transmitting relation thereto. The upper surfaces of these blocks are provided with short transversely extending ribs 118, the ribs on opposite sides being staggered. When one of these ribs passes under the end of a spring, the pressure exerted by the latter will rock the block and this rocking of the block while the metal is still soft, results in a loose connection between the casting and the mold which facilitates the removal of the casting.

Where the rocking mechanism is dispensed with the blocks may have flat bottoms as shown in Figures 5 and 10.

In order to break the groove metal, the upper surface of bottom member 15 is provided with an upwardly convex portion like that designated by reference numeral 119 in Figure 20, located a short distance above wheel 115 where the metal is brittle after having been notched and chilled. When the blocks are moved in the direction of the arrow, they are first turned upwardly so as to bend the groove metal at point H and this, due to the brittle condition of the metal, tends to weaken it and break it and this is further augmented at the next joint. As the blocks pass over the hump the groove metal will be put under tension which completes the breaking thereof.

In Figures 21 and 22, different arrangements of the blocks have been shown. In Figure 21, the groove 48 is positioned to the outside of channel A and in 22 the groove is positioned towards the inside of channel A.

The amount of cooling can be adjusted by varying the position at which the metal is poured with respect to the length of the row of blocks. It is evident that the nearer to the top of the row the metal is poured, the shorter time it will have for cooling and this makes it possible to give the castings the best possible heat treatment to obtain the optimum grain structure.

By increasing or decreasing the amount of metal in the mold blocks with respect to the size of the balls or other castings, and by substituting copper or a suitable alloy, the amount

of chill and the resultant grain structure can be modified within reasonable limits.

Due to the fact that the molds are separated at the upper end of the row in channel A, the operator has an opportunity to employ a hammer or a chisel or any other suitable tool to loosen the casting from the mold in case it should not fall out of its own accord.

The sprues 103 become quite hard and brittle due to the chilling action and are easily broken at their narrowest points and may be provided with a restricted area at this point, as indicated by reference numeral 120.

In the present embodiment the mold blocks have been shown and described as made from cast iron and in Figure 8 a block having a copper insert 52 has been shown. Its use is contemplated where a very rapid chill is desired.

Since the blocks are arranged in rows and are moved by means of pressure exerted on an end block, it is evident that the blocks are free to expand and contract in response to temperature changes.

In addition to the spring 34 and as a further 25 and an adjustable means for returning the cross head 29 and associated parts, a weight Wt may be attached to the cross head and connected with the latter by a cable in such a manner that the pull due to the weight will supplement the 30 force exerted by the spring. This weight may be increased or decreased to effect the proper operation with different inclinations of the machine.

Attention is called to the fact that when the 35 mold blocks are heated due to their contact with the molten metal, the latter has its temperature decreased and the groove metal is therefore contracting at the time the blocks are expanding and since the groove metal cools fast 40 compared to the rate at which the temperature of the mold blocks changes, the tensional forces thus exerted on the groove metal tends to break it at points 114 where it has been weakened by the action of the notching wheel 106.

In the construction shown and described, the 45 mold blocks are readily removable as they merely rest on the bottoms of the channels. A block can be removed at any time and replaced by another without affecting the operation.

Referring again to Figures 9 and 10, attention 50 is called to the fact that the mold block 47 can be made from copper and the top 54 from cast iron. Since copper is a much better conductor of heat than the iron, the same relation between 55 the heat conductivities of the two parts will be preserved.

Attention is directed to the fact that in the construction shown and described, the molds are pushed upwardly along an inclined path by a force applied to the lowermost mold in the row and this allows for expansion and contraction in response to temperature changes and as a result the molds are always held in contact with a constant force during the entire range of temperature variation.

Having described the invention, what is claimed as new is:

1. A ball casting machine comprising, in combination, an elongated frame, inclined at an angle to the horizontal, having its upper surface provided with two spaced parallel guide channels, a row of mold blocks positioned in each channel, in end contacting relation, said blocks having their contacting surfaces provided with complementary mold depressions and gate openings

11

and a channel in their upper surfaces connecting said gate openings, a power reciprocated member having one abutment for intermittently moving the mold blocks upwardly in one channel and a second abutment for moving mold blocks downwardly in the other, each reciprocation moving the rows of blocks the length of a block, reciprocating transfer mechanism at the lower end of the frame for moving blocks from the lower end of the downwardly moving row to the lower end of the upwardly moving row, means for filling the molds in the upwardly moving row with molten metal, means for separating the uppermost block in the upwardly moving row from its adjacent block to permit the casting to be removed, and a second reciprocating transfer mechanism for moving the separated block in the upwardly moving row to the upper end of the downwardly moving row of blocks, whereby an intermittent circulation and separation of the blocks is effected.

2. An automatic ball casting machine in accordance with claim 1 in which a groove metal connection is formed which connects a row of several spaced gates and in which means comprising a toothed wheel positioned for rotation with its teeth projecting into the groove metal, is provided for chilling and at least partially severing the groove metal to facilitate breaking thereof.

3. An automatic ball casting machine in accordance with claim 2 in which the bottom of the channel containing the upwardly moving blocks is provided with an upwardly convex portion positioned above the chilling and severing device for bending the groove metal to effect a breaking thereof.

4. An automatic ball casting machine in accordance with claim 1 including means for effecting a relative movement of the blocks with respect to each other while the metal is setting to facilitate removal of the castings from the molds.

5. An automatic ball casting machine in accordance with claim 1 in which the under surface of each block is transversely convex and in which means is provided for effecting a rocking movement of each block relative to its adjacent

12

blocks while the metal is setting, whereby the removal of the casting is facilitated.

6. An automatic ball casting machine in accordance with claim 1 in which the sides and bottom of the guide channels are formed from hollow members through which water may be flowed for effecting a cooling of the blocks, the hollow members at the sides being a fixed distance apart throughout their length and the hollow member at the bottom extending between the lower edges of the hollow members at the sides to form a channel with a closed bottom and an open top, the channel being of such size that a row of blocks may slide therein with the sides of a block in engagement with the hollow members at the sides, and the bottom of the block in engagement with the hollow member at the bottom.

7. An automatic ball casting machine in accordance with claim 1 wherein the channel in the upper surfaces of the molds is disposed relative to the gate openings in a manner to effect rotary movement of the molten metal as it flows down a gate opening.

WILLARD C. BRINTON.
